MECHANICAL TOY

Giuseppe Manassero, New York, N. Y.

Application April 7, 1932. Serial No. 603,708

3 Claims. (Cl. 273—101)

My invention consists in a mechanism comprising means for catapulting an object, such as a ball, indicating or recording means, and a single operating means, whereby both said first named means are simultaneously operated. More particularly, my invention has for its purpose to produce a mechanical toy to represent a basketball game, in which by the quick depression of a single lever a light ball is catapulted into the air in the direction of a small "basket", while at the same time an indicator is moved forward one step to indicate the number of times the ball has been thrown.

The toy is mainly constructed of pieces of wire and stamped out portions of sheet metal easy to be assembled so that it can be cheaply and quickly manufactured and readily taken apart to be packed in a small compass.

For a better understanding of my invention, I refer to the annexed drawing, in which, by way of illustration, I have shown an embodiment of the invention and in which Fig. 1 is a top plan view of a miniature basket ball game, Fig. 2 a side-view of the same and Fig. 3 a detail view 25 of the "basket" holder.

In Figs. 1 and 2, there is shown at 1 a base-plate, which may be made of wood, card-board, or other suitable material. At the four corners thereof are provided short feet 2 each containing a small bore for the reception of the bent-off portion of a wire extending along the longer side of base-plate 1, said wires being shown at 3 and 4. These wires, together with a connecting end wire, shown at 5, constitute a fence around three sides of the base-plate leaving one side open at the forward end. At 6 is shown a narrow bushing fastened to the plate and adapted to receive the lower bent-off portion of an upright shown at 7, which may be made of sheet-metal of chan- 40 nel-cross-section to give it sufficient rigidity. At 8 is shown a flat member, made, like base-plate 1, of wood, card-board, or the like and having secured to its rear side two short sleeves 9 and 10 adapted to receive the upper end of upright 7 45 so as to frictionally engage the same thereby holding the flat member 8 in position thereon. At 11 is shown the "basket" made of a single piece of wire suitably bent and twisted to form a round opening 12 and supporting arms 13 having bent-off ends 14 adapted to be passed through apertures 15 in the flat member 8 so as to be clamped in place thereon, as shown in Fig. 2.

The principal mechanism now to be described is situated on the forward portion of base-plate 55 1 and is composed of the following parts:

1. The catapult which is made of a piece of thin sheet metal so shaped as to form a narrow arm 16 carrying at its forward end a slightly concave round disk 17 and being expanded at its rear end to form two lugs 18 and 19 which, by means of two rivet-like pins 20 and 21 are loosely attached to base-plate 1 which, as is clearly shown in Fig. 1, is provided with a longitudinal slot 22 through which the narrow arm 16 projects below the bottom side of base-plate 1. (See Fig. 2.)

2. The indicating means, which comprises a rotatable annular member 23, stamped out of sheet-metal and provided along its periphery with a plurality of successive tongues that have been turned back so as to constitute relatively spaced small abutments 24. Toward the center of member 23 and beyond the center, extends a pointer 25 provided with a hole for member 23 to be rotatably mounted on a stem 26 projecting through base-plate 1 from below and fastened thereto. At 27 is shown a peculiarly-shaped piece of wire formed with a triangular portion 28 and ending in a straight finger 29, the forward end of which is adapted to engage between adjacent abutments 24 of the annular member 23. At its other end, 70 the wire 27 is turned back to form an arm 30 terminating in an eye 31 engaging the crank-shaped portion 32^a of a wire 32 extending partly across base-plate 1 parallel with its forward edge and being held in place by two lugs 33 and 34 formed with holes to receive the wire 32. At 32^a, wire 32 is bent off at right angles and passes through an aperture 35 in base-plate 1 below the same, at first extending downwards and then at 75 right angles parallel to its upper portion, whereupon the wire is bent again, this time upwards so as to project through an aperture 36 in base-plate 1, where it is formed with an eye 37 engaging the wire 27.

3. The actuating member consisting of a lever arm 38 formed with a cradle 39 being fulcrumed to the top of base-plate 1 at 40 and 40' and being provided with a broad finger-piece 41, adapted to be struck by a finger as shown in Fig. 2. At its free rear end, the lever-arm 38 is provided or formed with a flat head 42 adapted to engage the narrow arm 16 of the catapult.

The lever-arm 38 is of such a length that in the normal position of the parts it is lowered, whereas the finger-piece 41 is raised.

The operation of the device will be readily understood from the foregoing description.

When the finger-piece 41 is struck a quick blow with a finger, the flat head 42 at the rear end of lever-arm 38 strikes the narrow arm 16

with considerable force so that a ball, indicated at 43 in Fig. 2 by the broken lines, resting on the round disk 17 is thrown high up into the air. If the finger-piece 41 has been struck with just the right force, the ball 43 will in being thrown into the air, describe the trajectory 44 shown in Fig. 2 and will drop into the "basket" 11. While the arm 16 is struck by the flat head 42 of the lever-arm 38, the latter simultaneously strikes the wire 32 which thereby is rocked within its lugs 33 and 34 and through its arm extending upwardly through the aperture 36 imparts to the peculiarly bent wire 27 a compound movement in such a way that its finger 29 first descends between two adjacent abutments 24 of the annular member 23 and immediately thereupon makes a lateral motion so as to thereby move or rotate the annular member 23 about stem 26 one step in an anti-clockwise direction. In this manner, the pointer 25 of the annular member 23 will indicate the number of times, the finger-piece 41 has been struck and the ball 43 thrown.

As shown by Fig. 3, there may be provided, if desired, a recording mechanism on the "basket" holder 8. As shown in said figure and also in Figs. 1 and 2, a small catch is provided at 45, which, when a ball drops into the "basket" is struck thereby and by suitable means not shown actuates a recording mechanism 46 provided with a pointer 47.

If it is desired that the ball when thrown into the "basket" should be caught, a small net indicated at 48 in Fig. 2 may be provided.

Obviously, my invention is not limited to the embodiment shown on the drawing as the same may be varied in many different ways both regarding the construction and general arrangement without a departure from the essence of my invention.

40 I claim:

1. In an amusement device of the projectile game piece type, a target to receive a projected game piece comprising a support disposed in a vertical plane and having a pair of spaced openings formed therethrough, and a single length of material bent to form a horizontally disposed game piece receiving ring and terminal arms for

engagement in the openings of said support to hold the target in operative position, the said terminal arms extending from opposite sides of the ring first downwardly and inwardly relative to the support, then upwardly, then rearwardly and then downwardly to provide portions to rest against the front of the support and hook portions to engage the openings and the rear of the support to hold the target firmly in an operative position.

2. In an amusement device of the projectile game piece type, a base having a slot, an arm having a lug at one end resting upon the top of the base and at its other end having a game piece holder normally resting upon the top of the base, the lug being apertured, a fastener extending loosely through the aperture of said lug and into the base and loosely connecting the arm to the base for limited vertical swinging and lateral movements, an intermediate portion of said arm extending through the slot in the base and normally below the bottom face of the base, and an actuating lever pivoted intermediate its ends to the base and having one end portion thereof underlying the arm intermediate the ends thereof, whereby depression of the other end of said lever is effective to impart upward swinging movement to the arm to project a game piece supported thereon.

3. In an amusement device of the projectile game piece type, a base having a slot, an arm having a pair of apertured lugs at one end thereof resting upon the top of the base and at its other end having a game piece holder, fasteners extending through the lug apertures into the base and loosely connecting the arm to the base for limited vertical swinging and lateral movements, an intermediate portion of said arm extending through the slot in the base and normally below the bottom face of the base, and an actuating lever pivoted intermediate its ends to the base and having one end portion thereof underlying the arm intermediate the ends thereof, whereby depression of the other end of said lever is effective to impart upward swinging movement to the arm to project a game piece supported thereon.
